UNITED STATES PATENT OFFICE.

FRANZ BEDUWÉ, OF LIEGE, BELGIUM.

APPLIANCE FOR RAISING SOLID BODIES.

1,042,180.

Specification of Letters Patent. Patented Oct. 22, 1912.

Application filed May 17, 1911. Serial No. 627,821.

To all whom it may concern:

Be it known that I, FRANZ BEDUWÉ, subject of the King of Belgium, residing at Liege, Belgium, have invented certain new and useful Improvements in Appliances for Raising Solid Bodies; and I do hereby declare the following to be a full, clear, and exact description of the invention, such as will enable others skilled in the art to which it appertains to make and use the same.

The present invention relates to improvements in elevating mechanism or devices of that character in which by the action of a suitable body of compressed air admitted into a conduit or discharge pipe a stream of water, and solid materials can be withdrawn from a pit or receptacle in which they have been collected.

In the handling or transportation of solid granular or fragmentary materials, for example, gravel, sand, mineral, coal, coke, etc., it is customary to create a stream of water into which the materials to be moved are discharged and to collect such mixed water and solid materials in pits or tanks into which extend the intake ends of elevators of the character above referred to.

As commonly constructed, considerable inconvenience is experienced by reason of the fact that it is often impossible to so regulate the admission and withdrawal of material from such a pit or receptacle that there will not be an accumulation of the solid material of such an amount as to choke the intake end of the elevator conduit and frequently the entire apparatus is rendered inoperative by such an accumulation.

The object of the present invention is to provide a construction by which such accidental stoppage of the elevator devices is rendered impossible.

In the accompanying drawing there is illustrated one embodiment of the invention, the pit or receptacle and a portion of the elevator tubes being shown in vertical section.

As shown the water and solid material are collected in a suitable pit or receptacle, the interior of which is divided into two compartments by a vertically arranged partition, the lower end of which is some distance above the floor or bottom of the receptacle. The elevating devices, which extend into that compartment of the pit or receptacle which is separated from the inlet thereto by the vertical partition, comprise a relatively fixed

or stationary tube *a* supported by suitable means at the upper end of the receptacle and provided with a laterally extending discharge branch *b*, and an intake tubular section *c*, which is telescopically connected with the section *a* and extends vertically within the pit or receptacle having its lower open end extending below the lower edge of the partition in said receptacle. Within the sections *a*, *c*, of the elevator tube is arranged a pipe or conduit *d* adapted to be connected by a flexible coupling *g* with means for supplying air under pressure. Said air conduit is connected with and forms the support for the lower intake section *c* of the elevator tube and the discharge openings from said pipe *d* are at the lower end thereof adjacent the inlet to the elevator tube.

By means of a counterbalance weight *f* connected with the air conduit *d*, by a cable *e*, the intake section *c* of the elevator is maintained at any desired adjustment and by this means the height of the lower end of said tube section from the bottom of the tank or receptacle can be varied as desired.

It will be understood that in operation compressed air discharged into the lower portion of the elevator tube will create an upward current therein, causing a stream of water and solid material to flow outward from the tank or receptacle through the discharge pipe *b*. In event that there is an increase in the volume of the stream of water and material flowing into the receptacle sufficiently to cause an undesirable accumulation of the solid particles in the bottom of the pit, the intake section of the elevator is readily raised and if desired such section can be lowered farther into the pit.

It will then be seen that the present invention provides an apparatus of the type and character referred to in which clogging or stopping of the elevator by reason of accumulation of solid material in the collection pit or receptacle is readily prevented.

It has heretofore been proposed to make the suction pipes or tubes of dredges from a plurality of sections telescopically connected so that the lowest or bottom section would accommodate itself to the unevenness of the surface on which it rests or over which it is moved in use. Also in such dredges it has been proposed to direct a stream of water into the solid matter to be dredged for the purpose of loosening it and permitting it to be carried upward through

a suction pipe. Devices of this character, however, are quite different from the subject of the present invention which, as hereinbefore noted, is designed particularly for 5 the handling of such material as sand, coal, etc., which has been collected in a pit or receptacle into which it is carried by a stream of water. Such pits or receptacles are necessarily of relatively restricted area and for 10 reasons pointed out hereinbefore, it is very important in this particular art to be able to adjust the inward end of the elevating mechanism employed for carrying the granular material from the pit.

15 Having thus described the invention what is claimed is:

1. In an apparatus of the character described, the combination with a pit or receptacle for water and granular or fragmentary solid material, of an elevator comprising a sectional tube that extends into the receptacle, the lower intake section of said tube being telescopically connected with the section above it, a conduit extending into 20 and connected with the intake section of the tube for supplying air under pressure to said intake section, and a counterbalance 25 connected with said conduit.

2. In an apparatus of the character described, the combination of a pit or receptacle for water and granular or fragmentary solid material, which receptacle is divided into two compartments by a vertically 30 arranged partition, the lower edge of

which is out of contact with the bottom of 35 the receptacle, of a discharge conduit extending into the compartment of said receptacle which is separated from the inlet thereto by said partition, the lower end of 40 said conduit being telescopically supported and adapted to extend below the lower edge of said partition, and a conduit for discharging air under pressure into said discharge pipe adjacent the lower intake end 45 thereof, substantially as and for the purpose described.

3. In an apparatus of the character described, the combination of a pit or receptacle for water and granular or fragmentary solid material, which receptacle is divided 50 into two compartments by a vertically arranged partition, the lower edge of which is out of contact with the bottom of the receptacle, an elevator comprising a sectional tube that extends into the compartment of 55 said receptacle which is separated from the inlet thereto by said partition, the lower section of said tube being telescopically supported, and a conduit for discharging gas under pressure into said discharge pipe, 60 substantially as and for the purpose described.

In testimony whereof I affix my signature in presence of two witnesses.

FRANZ BEDUWE.
